VICTOR WEBER,
By Lawrence D. Englund
ATTORNEY.

UNITED STATES PATENT OFFICE

2,135,864

CIRCUIT BREAKER

Victor Weber, St. Louis, Mo., assignor to The Emerson Electric Mfg. Co., St. Louis, Mo., a corporation of Missouri

Application September 23, 1936, Serial No. 102,093

16 Claims. (Cl. 200—113)

The present invention relates generally to circuit breakers, and more particularly to a thermally actuatable circuit breaker which includes automatic reset mechanism and snap make-and-break action.

5 An object of the present invention is to provide a thermally-actuatable circuit breaker which is adapted to interrupt the electrical circuit of an energy-translating device upon an excessive current therethrough or upon a dangerous internal overheating of the device.

Another object is to provide a thermally-actuatable circuit breaker which includes means for automatically resetting the device subsequent 10 to a current interruption action thereof.

Another object is to provide a thermally-actuatable circuit breaker which includes a heating element adapted to actuate the circuit breaker by current passing therethrough.

20 Another object is to provide a thermally-actuatable circuit breaker which includes over-center snap mechanism for closing and opening the contacts thereof to prevent arcing.

Another object is to provide a thermally-actuatable circuit breaker which is adapted to 25 efficiently and effectively protect an energy-translating device, as a motor, under a variety of conditions.

Another object is to provide a thermally-actuatable circuit breaker which is compact in 30 structure, cheap to manufacture and adapted to fulfill all of the purposes and advantages sought therefor.

Other objects and advantages will be apparent 35 from the following description, taken in conjunction with the accompanying drawing, in which

Fig. 1 is a plan view of a thermally-actuatable circuit breaker constructed in line with the present invention.

40 Fig. 2 is a side elevation of the device shown in Fig. 1.

Fig. 3 is a section on the line 3—3 of Fig. 1, showing the elements in positions whereby the contacts are closed.

45 Fig. 4 is likewise a section on the line 3—3 of Fig. 1, showing the elements in positions whereby the contacts are open.

Fig. 5 is a section on the line 5—5 of Fig. 2.

Fig. 6 is a section on the line 6—6 of Fig. 4.

50 Fig. 7 is a plan view of preferred embodiments of a pivot plate and an upper switch blade in assembled relation.

Fig. 8 is a plan view of a preferred embodiment of a lower switch blade and a supporting plate 55 therefor in assembled relation.

Fig. 9 is a plan view of preferred embodiments of a U-shaped bracket support.

Fig. 10 is a perspective of a preferred embodiment of a connecting plate.

Referring more particularly to the drawing by 5 reference numerals, 11 represents a base preferably of a configuration shown in Fig. 1 which is adapted to support in operative relation the elements of the instant thermally-actuatable circuit breaker. A support, generally indicated 12, of 10 U-shaped transverse cross-section rests on the base 11 and is connected thereto by nut and bolt means 13 extending through a horizontal flange 14 on the one side and by an extension 15 of the vertical leg 17 extending into an opening 16 in 15 the base 11 on the other side. The support 12 further includes a horizontal bight 19 and a second leg 18. A bimetallic element 20 of generally elongated rectangular configuration is connected at one end by bolt and nut means 21, or the 20 like, to the bight 19 of the support 12. The bimetallic member 20 has a major notch 22 and opposed minor notches 23 in the free end for a purpose to be described.

A U-shaped bracket, generally indicated 25, 25 rests on the base 11 beneath that end of the bimetallic member 20 which contains the notches 22 and 23, and is connected to the base by a brad 26 which extends through a centrally disposed hole 27 in the bracket and a hole 28 in 30 the base. Pivotal movement of the bracket about the brad 26 is prevented by a downwardly directed extension 29 of the bracket which nests in a hole 30 in the base. The bracket 25 includes a bight 31 which rests against the upper surface 35 of the base 11, vertically disposed legs 32 having opposed openings 33 therein, and generally upwardly directed opposed prongs 34 and 35.

A flat pivot plate 36 has trunnions 37 which are adapted to extend into the holes 33 of the bracket 40 25 to pivotally support the plate. The plate is cut out at 38 and is grooved at 39 and 40 along its transverse edges 41 and 42, respectively. An upper switch blade 44 of generally elongated rectangular configuration includes an outer peripheral portion 45 and an interiorly located tongue 46. The tongue 46 is spaced from the peripheral portion 45 by longitudinal slots 47 and a cut away portion 48. The peripheral portion 45 includes an interior transverse edge 49 which is 45 adapted to fit within the groove 39. The tongue 46 terminates in a transverse edge 50 which is 50 opposed to the edge 49 and is adapted to fit within the groove 40. The distance between the edge 49 and the edge 50 is predeterminedly less 55

than the distance between the apexes of the grooves 39 and 40 so that the tongue assumes, when in assembled position upon the flat plate 36, the bowed position shown in Fig. 2, the operative purpose of which will be subsequently described. At the end of the blade 44 remote from its connection with the plate 36, there is a contact 51. A flange or apron 52 extends at right angles to and along each longitudinal side of the peripheral portion 45 to render that portion substantially rigid.

A connecting plate 53 of rectangular shape, as is shown in Fig. 10, had two sets of opposed notches 54 and 55, respectively. The notches 54 engage the notch 22 of the bimetallic member 20, and the notches 55 engage the pivotal plate 36 through the cut out 38, as will be apparent from an inspection of Fig. 6. The connecting plate 53 is held in position by means of a strap 56, which is connected to the bimetallic member 20 and engages in the notches 23.

A lower switch blade support 58 rests on the base 11 beneath the bimetallic member 20 and the upper blade 44 and is connected thereto by brads 59, or the like, intermediate the bracket 25 and the support 12. The support 58 is generally rectangular in shape and includes the connecting portion 60 and the raised portion 61, and is cut away centrally to provide an opening 62. A lower switch blade 64 is connected to the support 58 by the aforementioned securing means 59 and extends through the opening 62 and beneath the raised portion 61, as can be seen from Figs. 4 and 8. A contact 65 is fixed to the free end of the blade 64.

A sinuous heater element 67 is connected to the base 11 at terminals 68 and 69. The heater element is disposed to lie beneath or above the bimetallic element or member 20, the illustration at Figs. 1 and 2 showing it beneath. Leads 70 and 71 for the heater element 67 are connected to the terminals 68 and 69, respectively. A lead 72 is connected to the brad 26 which thereby serves as a terminal, and a lead 73 is connected to one of the brads 59 which likewise thereby serves as a terminal.

Operation

The instant thermally-actuated circuit breaker is adapted to be used with energy-translating devices generally, but it is particularly useful in conjunction with a motor. In practice, the circuit breaker is disposed within a casing of a motor in a position to receive the full effect of ambient heat. The bimetallic member 20 is adapted to flex outwardly from the base 11 through a predetermined temperature range reached either from heat within the motor casing, as that which accumulates from a continuous overload of the motor, or from a short circuit in the line, or a stoppage of the armature, in which case a large current would be passed through the windings and a proportionate amount through the heater element 67.

It is thus apparent that the present invention is constructed to protect a motor under varied operating conditions. The mechanical functioning of the circuit breaker is distinctly novel and includes an over-center snap-action. As has been described, the bimetallic member 20 is connected in a positive manner to the pivot plate 36 by means of the connecting plate 53. Hence, when the free end of the bimetallic member 20 moves away from the base 11, the plate 36 will be pivoted about its trunnion support 37, the groove

39 and its associated blade edge 49 likewise moving away from the base 11 and the groove 40 and its associated tongue edge 50 moving toward the base in this pivotal action. The switch blade 44 is connected to the plate 36 in an over-center relation, the blade 44 pivoting along the edge 49 within the groove 39 and being biased to the one side or the other of center position by means of the edge 50 of the bowed tongue 46 acting within the groove 40. The pivotal movement of the plate 36 is limited clockwise by the stop 35 and counterclockwise by the stop 34.

Referring to Fig. 3, the elements are shown in positions wherein the contacts 51 and 65 are in closed position. That point established by the apex of the groove 40 is above a line between the point established by the apex of the groove 39 and the point of connection of the contact 51 to the end of the blade 44. The bowed tongue 46 biases the plate 36 toward counterclockwise pivotal action and hence forces the contact 51 into engagement with the contact 65 in clockwise pivotal movement of the blade 44 about the edge 49.

Upon sufficient amount of heat being supplied to the bimetallic member 20, the free end moves outwardly, as has been stated, from the base 11, thereby pivoting the plate 36 clockwise about its trunnions 37 until it encounters the stop 35, which prevents further movement. In this movement, that aforesaid point established by the apex of the groove 40 moves across the line extending between that point established by the groove 39 and that point established by the connection of the contact 51 to the end of the blade 44. On passing this line, the direction of the force applied by the bowed tongue 46 changes, and the bias against the plate 36 becomes clockwise. Hence, the contact 51 will be snapped away from the contact 65 and up against the bolts 21 as 40 stops. The snapping open of the contacts 51 and 65, of course, interrupts the electrical circuit of the motor, thereby stopping the same. As the temperature of the air surrounding the bimetallic member 20 drops, the free end of the member 45 returns to its normal position, thereby pivoting the plate 36 in a counterclockwise direction until it encounters the stop 34, which carries the tongue edge 50 upwardly across center to snap the contact 51 into closed relation with the contact 65. 50 The circuit breaker is thus automatic in its operations of opening and closing. It is apparent that the heater element 67 may be associated in any desired manner with the circuit breaker.

It is clear that a thermally-actuated circuit breaker has been provided which achieves all of the advantages and purposes sought. It is to be understood that the above description and the accompanying drawing have been given by way of example, and not by way of limitation, the invention being limited only by the following claims.

What I claim is:

1. A circuit breaker comprising a pivoted member, an element pivoted to said member and carrying a contact at a free end, said pivotal connection between said member and said element including two spaced cooperating groove and edge connections, a second contact disposed to cooperate with said first contact, and means to effect snap pivotal movement of said element including a thermally-actuated member.

2. A circuit breaker comprising a base, a support thereon, a bimetallic member fixed to the support and extending over the base, a bracket 75

on the base, a plate pivoted to the bracket, a switch blade pivoted to and supported by the plate and carrying a contact, a second contact, and a connection between the bimetallic member and the plate to that side of the plate pivot just remote from the contacts.

3. A circuit breaker comprising a base, a bimetallic member supported thereon, a member pivotably supported on the base, an element supported by said member for pivotal movement relative thereto and carrying a contact, a second contact, and a connection between said bimetallic member and said pivoted member, whereby movement of said bimetallic member will effect pivotal movements of the pivoted member and the element in opposite directions to break or make the contacts.

4. A circuit breaker comprising a base, a bracket thereon, a plate pivoted on the bracket, a resilient switch blade supported by the plate by supporting means including two groove and edge connections whereby the switch blade is biased out of the plane of the plate to one side or the other, means defining the limits of movement of the free end of the blade, a contact on the blade, a second contact, and means to move said blade alternately into its biased positions to snap make and break said contacts.

5. A circuit breaker comprising a base, a bracket supported thereon, a plate pivoted to the bracket, a switch blade pivoted to and supported by the plate and carrying at its free end a contact, a second contact disposed to cooperate with the first contact, a thermally-actuated member supported by the base, and a connecting plate between the said member and the plate, so that thermally induced movement of the said member is transmitted to the plate to effect breaking and making of the contacts.

6. A circuit breaker comprising a base, a bracket thereon including opposed upstanding legs, a plate pivoted to the legs, said plate having grooves in its edges parallel to the pivot axis, a switch blade including a cut away portion and an interiorly disposed resilient tongue, the distance between the end of the tongue and an opposed interior edge being less than the distance between the said grooves, said blade being pivotally supported by the said plate by means of the said interior edge and the edge of the tongue resting within the said grooves, a contact on the blade remote from the pivotal support, a second contact, means limiting the movement of the free end of the blade, and thermally-actuated means to pivot the blade through pivotal movement of the plate to break-and-make the contacts.

7. In a device of the kind described, a switch blade comprising an elongated element having an interior portion adjacent one end cut away and having a tongue formed from the remaining interior portion, and a contact at that end of the element remote from the cut away portion.

8. A circuit breaker comprising a base, a bracket supported thereon, a plate pivoted to said bracket, said plate including a central cut away portion, a resilient switch blade pivoted to said plate and carrying a contact, a second contact, and means to effect pivotal movement of the plate to make and break the contacts including a thermally-actuated member and a connection between the said thermally-actuated member and the plate including a plate element having two pairs of opposed notches along parallel sides, one of said pair of notches be-

ing adapted to cooperate with notches in the said thermally-actuated member and the other pair with the said cut away portion of the said plate.

9. A circuit breaker comprising a base, a bracket supported thereon, a plate pivoted to the bracket, means to limit the pivotal movement of the plate, an element pivoted to the plate in a manner to effect over-center snap movement of the free end of the element, means to limit the movement of the free end of the element, a contact carried by the free end of said element, a second contact, and means for effecting pivotal movement of the plate and through the plate the element to make and break the contacts including a thermally-actuated member.

10. A circuit breaker comprising a support, a member pivoted thereon, a resilient element pivoted to said member, said last pivotal connection including grooves in opposed edges of the member and interior edges of the element, one of said edges being defined by an interior tongue integral with the element and said edges lying closer together unassembled than said grooves, so that in assembled relation said tongue is sprung to bias the element about its other interior edge as a pivot to either side of a center position in snap movement, means limiting the movement of the free end of the element, a contact on the free end of the element, a second cooperating contact, and means to effect snap movement to make and break the contacts without arcing.

11. A circuit breaker as defined in claim 10, said last named means including a thermally-actuated member.

12. A circuit breaker comprising a base, a support thereon, a bimetallic thermally-actuated member connected at one end to the support and extending along and spaced from the base, a U-bracket on the base beneath the free end of the member, a plate pivoted in the legs of the bracket, a resilient upper switch blade connected to the plate for movement thereby, means to limit pivotal movement of the pivoted plate, a plate member connecting the thermally-actuated member to the pivoted plate so that movement of the former pivots the latter, a resilient upwardly biased lower switch blade disposed beneath the upper switch blade, means to limit the upward movement of the lower blade, and cooperating contacts on the blades, said upper blade being so connected to the pivoted plate that thermally induced movement of the thermally-actuated member away from the base effects a snap breaking of the contacts and return movement towards the base a snap making of the contacts, thereby eliminating arcing of the contacts.

13. A circuit breaker including a base, a bracket fixed to the base, a bimetallic member fixed at one end to the bracket and extending along the base, a plate pivotally mounted on the base and disposed therebetween and the said member, a contact carrying blade pivotally supported by said plate, a second contact on the base cooperative with the contact on the blade, the pivotal connection between the blade and the plate being maintained through a resilient portion of said blade adapted to snap said blade and contact alternately to two extreme positions, and a rigid connection between the bimetallic member and the plate to effect said snap action upon movement of said member upon change in its temperature.

14. In a device of the kind described, a resilient switch blade, and a plate, said blade being pivotally supported on the plate, said blade including

an interiorly disposed resilient tongue abutting an edge of said plate at its free end and being under compression to maintain said blade on and in a plane at an angle to the plane of the plate.

- 5 15. In a device of the kind described, a base, a thermally actuatable member fixed to said base at one end, a plate pivoted to said base, a resilient switch blade pivotally mounted on said plate, said blade including a resilient tongue under compression abutting by a free end an edge of the plate to maintain said blade and plate in pivotal relation and to maintain said blade in a plane at an angle to said plate at one side thereof or the other, a contact on said base, a stop mounted in 10 spaced relation to said contact, an end of said blade being adapted to move between the contact and stop as limits, and a connection between the thermally actuatable member and the plate, whereby movement of said member upon change 15 in temperature therein pivots said plate to effect

a snap movement of said blade from its then one position to its other position.

16. A circuit breaker comprising a base, a bracket thereon, a member pivoted to the bracket, said member having two edges parallel to its pivot axis and on opposite sides thereof, a groove in each edge, a switch blade including a cut away portion and an interiorly disposed resilient tongue, the distance between the end of the tongue and an opposed interior edge being less 5 than the distance between the said grooves, said blade being pivotally supported by the said member by means of the said interior edge and the edge of the tongue resting within the said grooves, a contact on the blade remote from the 10 pivotal support, a second contact, and means to pivot said member to effect a snap action between the member and the switch blade to snap make and break the contacts.

VICTOR WEBER. 20
